ALTERNATING CURRENT ELECTRIC REGULATOR.

No. 423,553.

Patented Mar. 18, 1890.

UNITED STATES PATENT OFFICE.

LUDWIG GUTMANN, OF FORT WAYNE, INDIANA.

ALTERNATING-CURRENT ELECTRIC REGULATOR.

SPECIFICATION forming part of Letters Patent No. 423,553, dated March 18, 1890.

Application filed March 2, 1889. Serial No. 301,802. (No model.)

To all whom it may concern:

Be it known that I, LUDWIG GUTMANN, a subject of the Emperor of Germany, and a resident of Fort Wayne, in the county of Allen and State of Indiana, have invented certain new and useful Improvements in Alternating-Electric-Current Regulators, (Case 26,) of which the following is a specification.

This pressure-compensator has for its object

- 10 to cause any change of pressure and current required in any work-circuit to be effected at the source—viz., in the generating or inducing apparatus itself—without necessitating the interposition of regulating devices and
- 15 without cutting out or introducing of any coils into the circuit. The novelty of regulation consists in a subdivision of coils and the provision of means for changing the relationship of the various subdivisions. The length
- 20 chosen is such as to be fully capable of supplying the necessary pressure for the translating devices in circuit with it, and in this case all subdivisions are connected in series. If it is desired to decrease the pressure, means
- 25 are provided to place one or more of said subdivisions in parallel with the rest, whereby the pressure is reduced without the removal of any coil, or else to still further reduce the pressure. The connections of the coil may be
- 30 placed in parallel with the others, or else any other subdivision may be reversed, and then this reversed coil will act in opposition to the rest, with the effect of still further reducing the pressure compared with a coil connected in parallel. The means to make these changes are various. It may be a commutator or a reversing-switch, or a combination of reversing-switches, or connection or pole-changers in one single apparatus.
- 35 40 In the accompanying figures, Figure 1 represents a converter provided and connected with this regulating device. Figs. 2, 3, and 4 are diagram-connections, showing the different relationships between the coils. Fig. 5 is a simple reversing-switch.

In Figs. 1, 2, 3, and 4, A is a generator of alternating, pulsating, or intermittent currents. B is a converter connected thereto. C is the primary coil of said converter. D is the secondary coil. E are pole-changers; F F', the work or distributing circuit. G are translating

devices in circuit with circuits F F'. D' is the main part of the secondary coil. E are pole-changers in circuit with said coils. H H' H'' H''' are contact-blocks connected to terminals of the coils of a converter. K and L are subdivisions of the secondary coil. M, N, and O are contacts on a movable slide R. P P' are terminals of the circuit and of the converter-coil D.

In Fig. 5, S is a reversing-switch. T, U, and V are contact-points of the switch. W W' are contact-levers of switch. X X' are terminals of neighboring secondary coils of the converter.

In Fig. 1 the primary coil of the converter B is connected in multiple arc with a generator of alternating, pulsating, or intermittent currents, and the secondary coil D is connected to the distributing or work line F F', in which the translating devices G are operated. The secondary coil D has such a length of wire as to be fully capable of supplying the necessary pressure. The total length of coil D is subdivided, and the subdivisions connected to one another by means of grouping switches or pole-changers E. If the full pressure is required, then the changers E are so placed that the coils form a single series, as if they were wound of an uninterrupted wire.

If translating devices G represent lamps of which the brightness is desired to be lowered, I operate one or more changers E to effect the desired alteration by placing one or more of the sub-coils in parallel with one another, and should the reduction required have to be greater still, then I turn or advance changer E still more, whereby the connections of one or more sub-coils are reversed and react against the remaining part of the coil D.

It may be conveniently mentioned here that the changes can be either effected, first, by placing the sub-coils in parallel; second, by reversing the connections of one or more sub-coils with respect to the others; third, by placing one or more coils first in parallel, and for further reduction reverse the connection of the coils after being placed in parallel. It will be noticed that the most gradual change would be obtained by the first means.

If translating devices G are motors, the

effect of those changes would be to cause them to run slower. It is evident that this means of varying the pressure and current is not only applicable to converters, but also 5 choking magnets, motors, and generators.

Figs. 2, 3, and 4 show clearly the means for operation and changing of connection and regulation without any of the coils or sub-divisions needing to change place or to be 10 cut out of circuit. The ends of coils D are connected to line F F' at the points P P'. The ends of the subdivisions are joined to contact blocks H H'' H' H''' in such a manner that the left two blocks H and H' are the 15 terminals of the two starting-wires of the sub-coils K and L, while blocks H'' and H''' are the terminals of the other ends of the coils K and L. In contact with blocks H, H', H'', and H''' is a slide R, on which are mounted several metal pieces electrically insulated from one another. These pieces are M, N, and O.

In Fig. 2 it will be noticed that coil D is connected to the work-circuit F F', in which translating devices are connected, and the current would flow from coil D' to block H, sub-coil K, block H'', block M on slide R, block H', sub-coil L, block H''', block N, terminal P, line F, translating devices G, line F', and back to D', or vice versa, the current being alternating. This is the normal position or that for maximum pressure.

Fig. 3 shows the connections of the first reduction in pressure. Here it will be noticed that sub-coil K and sub-coil L are joined in 35 parallel through M and N O. In this position of slide R the current would flow from coil D' (to block H, block M of slide, and block H') at the same time, then to both sub-coils K and L, to blocks H'' and H''', to blocks O 40 and N on slide R, to terminal P, to line F, to translating devices G, line F', and back to coil D', or vice versa. To effect a still greater reduction in pressure, the slide is advanced still farther, as shown in Fig. 4. In this case block 45 N and block O of the slide do not touch the same contact-block as before, and the current flows now from coil D' to block H, sub-coil K, block H'', block O of slide, block H''', sub-coil L, block H', block N of slide, terminal P, line F, translating devices G, line F', and back to D', or vice versa. It will be noticed that L is now reversed or connected in opposition to coil K, and the work done by coil L in this 50 position is equivalent to cutting out two coils. 55 In these sketches the motion of the slide R is a rectilinear one; but if arranged in a circle or to rotate, the whole mechanism may be arranged into a small commutator.

Fig. 5 shows the connection of one of the 60 sub-coils K with a reversing-switch. The sub-coil K is connected to three contact-points T, U, and V. One end is connected to contact-point T, the other end to contact-point U, and a third connection is effected from contact T 65 to contact V. At the terminals X X' are con-

nected the ends of the neighboring coils D' and L.

In the connection shown in sketch the sub-coil K is inclosed normally in the same direction in the circuit; but when the switch-levers 70 W W' are placed in the position indicated by the dotted lines making contact with U and V, then the connection, and therefore, also, the action of sub-coil K, is reversed. The changes described and explained with the secondary 75 coil are not restricted to this coil, and can just as well be applied to the primary coil of a converter.

I claim as my invention—

1. In an alternating-current regulator, the 80 combination of an electric converter whose primary coils are included in a supply-circuit and whose secondary coil is subdivided, and the subdivisions thereof permanently included in a work-circuit and connected together 85 by pole-changers.

2. In an alternating-electric-current regulator, the combination of an electric converter, secondary coils therefor of different lengths, the shortest coils being connected among one 90 another and to the large coils by pole-changers, and the larger coils being connected to contact-blocks, and all of said coils being included in a work-circuit.

3. In a converter, the combination of a core, 95 a primary and secondary coil wound thereon, and each subdivided, the subdivisions of the two coils being connected electrically to one another by pole-changers, and the subdivisions of the primary coil being included in 100 the supply-circuit and of the secondary in the work-circuit.

4. In a converter, the combination of a secondary and primary coil, a core common to both, the primary coil being included in a 105 supply-circuit and the secondary being subdivided, the subdivisions being included in a work-circuit and permanently connected to one another by pole-changers.

5. The combination of multiple secondary 110 coils of a converter, all the coils being connected permanently in a work-circuit, and permanently connected to one another by pole-changers.

6. The combination, in an electric con- 115 verter, of a subdivided coil, and pole-changers connected in circuit with subdivisions of said coil.

7. In an alternating-current regulator, the combination of secondary coils, with pole-changers connecting together the coils, a work-circuit, and electrical connections between said coils and said work-circuit.

8. In a converter, the combination of a work-circuit, a primary coil, secondary coils 125 in series and connected to said work-circuit, and pole-changers between and connected to the said coils.

9. In an alternating-electric-current regu- 130 lator, the combination of a work-circuit, sec-

ondary coils of an electric converter, pole-changers connecting the coils together in series, and means, such as electric conductors, for maintaining electric connection between the remaining terminals of the coils and those of the said work-circuit.

5 In testimony that I claim the foregoing as

my invention I have signed my name in presence of two witnesses, this 23d day of February, 1889.

LUDWIG GUTMANN.
